UNITED STATES PATENT OFFICE.

CLEMENS GRAAFF, OF BERLIN, GERMANY, ASSIGNOR, BY MESNE ASSIGNMENTS, TO THE CHEMICAL FOUNDATION, INC., A CORPORATION OF DELAWARE.

CHEMICAL FIRE-EXTINGUISHER.

1,332,720.

Specification of Letters Patent.

Patented Mar. 2, 1920.

Application filed February 13, 1915, Serial No. 8,923. Renewed July 28, 1919. Serial No. 313,824.

To all whom it may concern:

Be it known that I, CLEMENS GRAAFF, a subject of the German Emperor, and residing at Linkstrasse 17, Berlin, Germany, have invented certain new and useful Improvements in Chemical Fire-Extinguishers, of which the following is a specification.

The present invention relates to new and useful improvements in fire-extinguishers, and has for its object to provide an extinguisher in which the propelling gas works with a maximum of efficiency.

A further object is to provide a simple structure for carrying out the principle involved.

Reference should now be had to the accompanying drawing which is a vertical sectional view.

1 indicates a container or extinguisher 20 casing containing extinguishing liquid. Extending into the container through a charging opening is the holder *g* within which is adapted to be placed the inset vessel *m*, containing the necessary chemicals for causing 25 a reaction when properly associated. Positioned below the inset vessel *m* is the plate *y* which is attached to the axially movable percussion pin *x*. The percussion pin *x* is positioned centrally of the cap closing the 30 filling opening of the container, and surrounded by a stuffing box.

When the percussion pin *x* is driven in, it 35 raises the inset vessel *m* and drives it against projection *z* which opens the inset vessel and causes the heretofore mentioned chemicals to come into intimate contact, whereupon a reaction takes place and gases are formed.

As a result of the reaction, the gases leave the inset vessel *m* and holder *g* under high

temperature and pressure, pass through the 40 perforations *i* in the end of the holder *g*, into the funnel 2 and thence into the tube 3 which extends above the level of the extinguishing liquid.

By this construction, it is obvious that the 45 propelling gases after being generated, will pass to the upper part 4 of the extinguisher without having to pass through the extinguishing liquid as has been done heretofore. It is also obvious by the construction de- 50 scribed and illustrated that the gases will contain the greater portion of the heat generated during the reaction, and hence be at their maximum pressure when they arrive at the upper portion 4 of the container 55 *z*. Any desirable means may be employed for delivering the extinguishing liquid when placed under pressure of the propelling gases.

Claim:

In a fire extinguisher, partly filled with extinguishing liquid, an inset vessel containing chemicals which are adapted to form propelling gases when properly associated, a holder having a perforated end plate for 60 said inset vessel, a projection upon said plate, means for forcing the inset vessel against said projection, a funnel positioned over said perforated plate and a tube leading from the funnel to a position above the sur- 65 face of the extinguishing liquid.

In testimony whereof I affix my signature in presence of two witnesses.

CLEMENS GRAAFF.
